UNITED STATES PATENT OFFICE.

WALTER D. COUCH, OF ATLANTA, GEORGIA, ASSIGNOR TO COUCH BROTHERS MANUFACTURING CO., OF ATLANTA, GEORGIA, A CORPORATION OF GEORGIA.

BACK-BAND HOOK.

1,289,676.

Specification of Letters Patent. Patented Dec. 31, 1918.

Application filed May 2, 1917. Serial No. 165,923.

To all whom it may concern:

Be it known that I, WALTER D. COUCH, a citizen of the United States, residing at Atlanta, Fulton county, State of Georgia, 5 have invented certain new and useful Improvements in Back-Band Hooks, of which the following is a specification.

This invention relates to buckles, particularly to buckles having hooks connected 10 therewith and which are adapted to be used with back bands, being known as back band hooks.

The hook member of the back band hook is designed to support the middle portion 15 of a trace chain to prevent its sagging, and the buckle member provides an adjustable means of attaching the hook to the back band so that the height of the chain may be regulated at will.

20 My invention provides a strong hook for supporting the chain and a simple and efficient buckle to which the hook is connected, which permits the same to be readily adjusted and which grips the back band more 25 securely and with less injury to the fabric when under strain, than devices of this class heretofore suggested.

The invention will be clearly disclosed in the following description, taken in connection 30 with the accompanying drawings, in which,

Figure 1 is a front view of my improved buckle attached to a back band;

Fig. 2 is a front view of the separated 35 members of the buckle, and

Fig. 3 is a section along the line 3—3 of Fig. 1.

The base portion 10 of the buckle and the bar 11 are of metal, preferably stampings 40 from sheet metal, the base portion being of thicker material than the bar because of the greater strain to which it is subjected. That portion of the base plate 10 which, together with the bar 11, comprises the buckle 45 proper, has the shape of a narrow rectangle, and is provided with two longitudinal parallel slots 12 and 13 of such length and width that the back band may be easily passed through. At the ends of the rib 14 between the slots 12 and 13 are hooks 15—15, preferably punched up from the material of the base 10 and extending around and over the ends of the bar 11 to prevent its separation

from the base, although allowing it to have a considerable play relatively thereto. 55

A tongue 16 projecting laterally from the rectangular portion of the base member 10 supports the trace chain hook 17. This hook is integral with the tongue and has its free end in the plane of the base member at or near the center of an opening 18 in the tongue which is considerably wider than the hook itself. This arrangement allows the link of a chain to be slipped over the hook, on which it is then held, with but little 65 danger of its coming off.

The bar 11 is rectangular in shape, being equal in length to the slots 12, 13 and having a width approximately equal to the distance between the outer longitudinal edges of the 70 slots, measured by a line perpendicular to these edges.

Projections 19, 19 and 20, 20 at the corners of the bar 11 form stops which, in connection with the hooks 15, 15, against which 75 they are adapted to abut, limit the sidewise movement of the bar 11 relatively to the base member 10. The projections 19, 19 have lateral extensions which assist in preventing excessive tilting of the bar when 80 the buckle is in use.

When the buckle is attached to a back band the latter passes from the back of the same through the slot 12, around the bar 11, and back through the slot 13, as is clearly 85 shown in Figs. 1 and 3. When weight is put on the hook the pull of the band tends to tilt the bar up around its upper edge and to drag it through the slot 12. The hooks 15, 15 and the extensions on the projections 90 19, 19 limit this tilting, the latter by bearing on the base plate 10 in advance of the upper edge of the bar 11. Naturally, the longer the extensions, the smaller the angle through which the bar may be tilted. 95

Being thus unable to tilt more than a few degrees, the pull of the band on the lower edge of the bar forces the upper edge against the fabric to frictionally engage it. As shown clearly in Fig. 3, the band makes 100 a reverse curve over the edge of slot 13 and around the lower edge of bar 11. This reverse curve formation causes the lower edge of the bar 11 to engage the band with a great amount of friction when weight is 105 placed on the hook. The buckle in this

manner grips the band with a firm, even grip and in such a way that the greater the pull on the hook the tighter the grip of the buckle on the band becomes.

5 To change the position of the buckle on the band, for instance, to raise it, the desired length of band is passed through the slot 12 from back to front of the buckle, and this surplus or loop thus formed in front 10 is taken up by drawing it through the slot 13 from front to back. The bar 11 has of course sufficient play under the hooks 15, 15 to allow the fabric to pass freely between the base 10 and the edges of the bar 11 in 15 making the adjustment.

The buckle above described is light in weight, simple, strong, and cheap to manufacture, and when used does not subject the fabric of the band to the harmful tearing action of teeth.

20 Although I have described my invention

in use as a back band hook it may obviously be used in other ways, for instance upon suspenders.

Having thus described the invention, what 25 is claimed and desired to be secured by Letters Patent is:

A buckle including in combination, a bar, a body portion formed to have a band passed therethrough looped around the bar and back 30 through the portion, said bar being substantially oblong in plan, the narrow ends each formed with a notch, said body portion having upstanding hooks each disposed in one of said notches and constructed to limit 35 movement of the bar away from said portion, said bar also having a notch formed at one long side for the band, the projections bounding the ends of said notch bearing on 40 said body portion and acting as fulcrums.

In testimony whereof I affix my signature.

WALTER D. COUCH.
